United States Patent Office.

WILLIAM F. PHELPS, OF WINONA, MINNESOTA.

Letters Patent No. 70,467, dated November 5, 1867.

FRAME FOR SUSPENDING MAPS.

The Schedule referred to in these Letters Patent and making part of the same.

TO ALL WHOM IT MAY CONCERN:

Be it known that I, WILLIAM F. PHELPS, of Winona, in the county of Winona, and State of Minnesota, have invented certain new and useful Improvements in Adjustable Map-Frames for Suspending Maps; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in making a new and useful adjustable frame for exhibiting maps, charts, drawings, paintings, or similar objects of any size required for use in schools, lecture-halls, or other rooms. In the drawings—

Figure 1 is a perspective view.

Figure 2 is a view of the rear, and

Figure 3 is a longitudinal vertical section of a portion of the standard E in connection with adjustable standard D.

In constructing my adjustable frame, I make a standard, E, of any suitable material, and provided with a basal support, F F, as shown in fig. 1. In order to facilitate the removal of the standard from one place to another casters may be used. In one side of the standard E, I make a dove-tailed or other suitable groove, H, and in the rear side of the groove make steps K K, as shown in fig. 3. Into this groove I slide a standard, D, having a spring, I, arranged so as to catch on to the steps K, and also provided with a handle projecting through the standard D, so as to release the catch when desired, as shown in fig. 3. The standard D, I also provide with a knob, J, by which to elevate it, or to lower it when the catch I is released. To the upper end of the standard D, I frame a horizontal bar, A, of wood or other suitable material, of any desired length, and provide it with a dove-tailed or other suitable groove, B B, extending its entire length, with a stop in the centre. This groove may be on the front or under side of the horizontal bar when in position. Within the grooves B B, I place sliding arms C C, provided with hooks G G, as shown in fig. 1. In constructing the horizontal bar A, and providing it with sliding arms C C, having hooks G G, it will be readily seen that instead of having the bar A grooved it may be made hollow so as to allow the arms C C to slide in the same, and have slots along which the hooks G G can pass.

My adjustable map-frame may be used with or without the standard E. When used in connection with it, the horizontal bar A can be elevated or lowered at pleasure by means of the knob J and spring I. When used without the standard E, it may be suspended from the ceiling, and elevated or lowered by pulleys and cords. When used, the hooks G G can be readily adjusted by moving the arms C C in or out, so as to hold a map, picture, painting, drawing, or any similar object desired to be exhibited.

Having thus described my invention, what I claim, is—

1. A horizontal bar, having longitudinally sliding arms provided with hooks, substantially as described and for the purpose set forth.
2. The standard E, having steps K, in connection with the sliding standard D and spring I, when arranged to operate as shown and described.
3. The adjustable standard E and horizontal bar A, provided with the sliding arms C C, when arranged to operate as described for the purpose set forth.

WILLIAM F. PHELPS.
